WRENCH HAVING PIVOTED AND SLIDABLE INNER JAW

Filed Sept. 10, 1946

wherein the jaws are formed by a single piece of metal, and the upper part of the milled nut is reinforced by a circular bead which is interiorly recessed to form an annular channel in which the movable jaw is supported. This jaw is in the form of a triangle $a-b-c$, the side $a-b$ of which is formed over a portion thereof as the

inner edge of the stay, and the outer edge of the stay is rigidly secured to the outer extremities of the flanges and bearing against the side of the shank opposite to the grooved side, the distance between the inner edge of the stay and the movable jaw

UNITED STATES PATENT OFFICE

WRENCH HAVING PIVOTED AND SLIDABLE INNER JAW

Paul Ollagnon, Saint-Etienne, France

Application September 10, 1946, Serial No. 695,949
In France September 13, 1945

2 Claims. (Cl. 81—92)

1

This invention relates to wrenches for pipes, tubes or other cylindrical apparatus, nuts and the like, of the kind in which the clamping action is increased to close the jaws about the work by pressure on the wrench handle in one direction and is decreased to release the work by pressure in the reverse direction, the movable jaw being adjustable towards and away from the fixed jaw by a nut which co-operates with a threaded part of the handle.

It is an object of the present invention to provide a novel or improved wrench of the kind defined above which, comprising only three relatively movable parts, and by avoiding the use of a hinge pivot and roller cage for the movable jaw, is of simple and robust construction and is easy to use.

According to the invention, in a wrench of the kind referred to, the movable jaw is formed with a portion seating within an annular groove in the nut and constituting a fulcrum about which said jaw is rockable, movement of said jaw away from the wrench handle being limited by an abutment on the jaw engageable with the back of said handle.

In order that the invention may be clearly understood and readily carried into effect, the same will hereinafter be more fully described with reference to the accompanying drawings, which show one embodiment thereof by way of example, and in which:

Figure 1 is a side view of the wrench showing the movable jaw in two different positions;

Figure 2 is a similar view to Figure 1 with parts in section;

Figure 3 is a transverse section on line 3—3 of Figure 1; and

Figure 4 is a transverse section on line 4—4 of Figure 2.

Referring now to the drawings, the wrench is shown as comprising a body 1 the head of which forms a fixed jaw extending at right angles to the body and the latter being fashioned at its other end in the form of a handle. The wrench body 1 is of rectangular section and is provided over a portion of its length intermediate the head and the handle with a screw thread which extends across the thickness of the body and with which co-operates a milled nut 2.

The upper part of the milled nut 2 is reinforced by a circular bead which is interiorly recessed to form an annular channel 2¹ in which the movable jaw 3 is supported. This jaw 3 is in the form of a triangle $a-b-c$, the side $a-b$ of which is formed over a portion thereof as the

toothed jaw proper, while the acute apex c rests in the annular channel 2¹. The movable jaw 3 is recessed longitudinally to allow for the passage of the wrench body 1, this recess being such that the jaw is rockable about the apex c through a small angle limited by the bottom of the recess and by a pin 4 secured to the jaw at a . The movable jaw 2 is shown as a single member, though it may be made of several pieces fitted together.

10 A longitudinal groove 5 formed along the handle on the jaw side accommodates one end of a spring the other end of which is engaged in a hole formed in the part $b-c$ of the movable jaw. The spring, which may be of the blade type or 15 may be of circular cross-section, serves firstly to maintain the apex c of the movable jaw seated within the channel 2¹ of the nut 2; secondly to urge the said jaw outwardly about its apex, this movement of the jaw being limited by engagement of the pin 4 with the wrench body; and 20 thirdly to prevent unintentional rotation of the nut 2.

In operation, the wrench functions in the following manner:

25 The milled nut 2 is actuated in such manner as to cause a pipe or other like element to be gripped between the two jaws. By the application of pressure on the back of the handle, i. e. that edge opposite the jaws, rocking movement of the 30 movable jaw 3 from the full line position shown in Figure 1 towards the chain line position is produced about the apex c , the jaws closing more tightly about the tube as this pressure is increased.

35 I claim:

1. A wrench comprising a shank including an angular jaw end rigid therewith, the shank having a longitudinal groove in the side thereof from which the jaw extends and a thread over a 40 part of the length thereof, a nut cooperating with said thread for adjustment longitudinally of the shank, an annular recess in the face of the nut opposite the angular jaw, a movable jaw of substantially triangular shape having a gripping 45 surface at the base of the triangle facing the co-operating surface of the angular jaw, the movable jaw having two flanges extending therefrom to embrace the shank between the angular jaw and the nut, the apex of the triangular movable jaw 50 pivotally engaging in the recess of the nut at a point adjacent the groove of the shank, a stay rigidly secured to the outer extremities of the flanges and bearing against the side of the shank opposite to the grooved side, the distance between the inner edge of the stay and the movable jaw

being greater than the coextensive dimension of the shank thereby to enable pivoting movement of the jaws apex in the annular nut recess, and an elongated spring slidably engaged in the groove and having cranked ends engaging respectively the movable jaw and the end of the nut remote from the recess.

2. A wrench comprising a shank including an angular jaw end rigid therewith, the shank having a thread over a part of the length thereof, a nut cooperating with said thread for adjustment longitudinally of the shank, an annular recess in the face of the nut opposite the angular jaw, a movable jaw comprising a body of substantially triangular shape and a pair of parallel flanges extending from the body and spaced to embrace the shank on either side thereof, the triangular body portion having a gripping surface at the base cooperating with the angular jaw, a stay rigidly secured to the outer extremities 15 of the flanges and bearing against the side of the shank remote from the movable jaw, the sides of the triangular body sloping to an acute angle

5 at the apex of which the body pivotally engages the annular recess of the nut, the distance between the stay and the body being greater than the width of the shank thereby to leave a clearance enabling pivoting movement of the movable jaw about the recess in response to thrust exerted upon the base towards the shank, and thereby to pivot the base towards the shank and to urge it towards the angular jaw thus to tighten the 10 grip between the jaws.
